United States Patent Office.

JOHN J. PHARES, OF ZIONSVILLE, INDIANA.

Letters Patent No. 89,337, dated April 27, 1869.

IMPROVEMENT IN RAILROAD-FARE BOXES.

The Schedule referred to in these Letters Patent and making part of the same.

To all whom it may concern:

Be it known that I, JOHN J. PHARES, of Zionsville, Boone county, and State of Indiana, have invented a new and useful Improved Mode of Collecting Railroad-Fare, which I call "Railroad Economy and Safety-Fund Box;" also, a New Form of Ticket, in connection with said box; and I do hereby declare that the following is a true and correct statement of the same, having reference to the accompanying drawings, and to the letters of reference marked thereon.

The nature of my invention consists in a plan of collecting fare on railroads, or any other use for which said invention may apply, and thus keeping an account of all moneys collected between railroad companies and their employees, and a great saving of ticket expenses, as said tickets will continue good for six days, commencing with letter M, on annexed drawings of fig. 4, at the bottom of said ticket, thus representing six days of the week, Monday being represented by letter M and Saturday by letter S at the top of said ticket.

To enable others skilled in the art to make and use my invention, I will proceed to describe its construction and operation.

I construct my machine after the following manner:

I make a tin can after the form of a bucket, as described by annexed drawings at fig. 1; also, having a door, as marked at letter H, having said door placed upon hinges, so as to be opened or closed at pleasure. I then make a revolving wheel, which I call ticket-carriage, as seen at fig. 2, annexed drawings.

I then divide the head of said wheel in as many divisions as I wish, as marked at letter I, representing the divisions, such divisions containing the numbers of all stations on any given road for which I desire said machine, each division containing the number of ten stations, as marked below in the apertures at letters J, thus making the numbers in the divisions to correspond with the apertures of letters J, said apertures containing ten ticket-boxes each, and the said ticket-boxes containing the numbers of the stations marked on the divisions above on carriage-head.

I also make a stationary handle, as seen in fig. 2, at letter K, for the purpose of lifting said carriage out of fig. 1.

I also place four knobs, lettered L, for the purpose of turning said carriage when in the hands of the conductor, having said box in his left arm, door open in front, conductor placing his thumb on knob nearest to him and fore-finger on the next, thus turning carriage from left to right, bringing any given point desired.

I also place a pivot on the bottom of carriage, as seen at letter M, for the purpose of allowing the carriage to turn inside of fig. 1, as seen at fig. 3.

I make my tickets, and so arrange them that each station has its own tickets, marked with the name of said station on the head of said tickets, as seen in fig. 4, at letter N, having four columns up and down said tickets, first column containing the month and first or second week, as the case may demand, as seen at letter O, same column, below the number of days in the week lettered M-T-W-T-F-S; second column, half-fare; third column, full-fare; fourth column, station.

The said ticket I make use of as follows:

I appoint a conductor I call No. 1, in whose hands I place my safety-fund box, containing my tickets for the different stations in said ticket-boxes, charging said conductor with all the tickets in said safety-fund box. I then allow said conductor to enter the cars, calling on each passenger for the point he or she desires to ride, at which time said conductor turns the carriage-wheel, brings up the number of said station, at which time he readily sees down the aperture the name of the station called, marked on the ticket-box, as seen in fig. 3, in open door, at letters P; from which he pulls a ticket, on which he marks, in station column, the number of station of which passenger gets on opposite the day of the week. In case of half-fare, he punches a square hole in half-fare column, opposite the number of station, which he places in the hands of said passenger, and thus passing from one passenger to another until all have tickets.

I then have a conductor I call No. 2, whom I appoint as cash and ticket collector, immediately following conductor No. 1, who calls on each passenger for ticket, and on seeing ticket readily sees the number marked by conductor No. 1, which enables him to call for the proper fare by seeing destination on the head of the ticket.

Said cash and tickets must balance with the safety-fund box in the hands of conductor No. 1 when returned to general ticket-agent.

What I claim as my invention, and desire to secure by Letters Patent, is—

1. The combination and arrangement of the covering can, fig. 1, with the revolving many-chambered ticket-holder, figs. 2 and 3, operating substantially as and for the purpose described.

2. In combination with the above, the employment of the system of tickets shown in fig. 4, substantially as described.

JOHN J. PHARES.
